Des. 235,400
Patented June 17, 1975

235,400

STANDARD AND BRACKET COMBINATION

Eugene Brown, 14 Willets Court,
Rockville Centre, N.Y. 11570

Original design application Feb. 25, 1972, Ser. No.
229,622, now Patent No. 231,295. Divided and this
application Apr. 4, 1974, Ser. No. 457,421

Term of patent 14 years

Int. Cl. D6—06

U.S. Cl. D6—114

FIG. 1 is a perspective view of a standard and bracket combination, showing my new design;

FIG. 2 is a front elevational view thereof;

FIG. 3 is a side elevational view thereof, the opposite side being identical thereto;

FIG. 4 is a perspective view of a second embodiment of a standard and bracket combination;

FIG. 5 is a front elevational view thereof;

FIG. 6 is a side elevational view thereof, the opposite side being identical thereto;

FIG. 7 is a top view of both embodiments of the standard and bracket combination; and

FIG. 8 is a bottom view of both of the embodiments of the standard and bracket combination.

The rear of all embodiments of the standard and bracket combination is unornamented.

This is a division of application Ser. No. 229,622, filed Feb. 25, 1972.

I claim:

A design for a standard and bracket combination, as shown and described.
